UNITED STATES PATENT OFFICE

104,974

DESIGN FOR A DRESS ENSEMBLE

Edward N. Tunick, New York, N. Y.

Application April 5, 1937, Serial No. 68,555

Term of patent 3½ years

To all whom it may concern:

Be it known that I, Edward N. Tunick, a citizen of the United States of America, residing in New York city, in the Borough of Manhattan, county and State of New York, have invented a new, original, and ornamental Design for a Dress Ensemble, of which the following is a specification, reference being had to the accompanying drawing, forming part thereof, wherein,

The rear portion of the dress unit is identical in appearance to the front portion as disclosed on the drawing, with the exception of buttons extending from the center of the bodice to a point below the waistline.

I claim:

The ornamental design for a dress ensemble, substantially as shown, and described.

EDWARD N. TUNICK.
